UNITED STATES PATENT OFFICE.

ROGER A. JENNINGS, OF GREENSBORO, NORTH CAROLINA.

DESIGN FOR A WARDROBE-DRESSER.

42,171.

Specification for Design.

Patented Feb. 13, 1912.

Application filed November 8, 1911. Serial No. 659,255. Term of patent 7 years.

To all whom it may concern:

Be it known that I, ROGER A. JENNINGS, a citizen of the United States, residing at Greensboro, in the county of Guilford and State of North Carolina, have invented a new, original, and ornamental Design for a Wardrobe-Dresser, of which the following is a specification, reference being had to the accompanying drawing, forming a part thereof.

The figure is a perspective view of what for convenience of reference I call a wardrobe dresser showing my new design.

I claim:

The ornamental design for a wardrobe dresser, as shown.

ROGER A. JENNINGS.
